UNITED STATES PATENT OFFICE.

WALTER P. MURPHY, OF NEW YORK, N. Y.

SHEET-METAL CAR DOOR.

Original application filed May 8, 1920, Serial No. 379,807. Divided and this application filed April 6, 1922. Serial No. 550,139.

To all whom it may concern:

Be it known that I, WALTER P. MURPHY, a citizen of the United States, residing at New York city, in the county of New York and State of New York, have invented certain new and useful Improvements in Sheet-Metal Car Doors, of which the following is a specification.

My invention relates to a sliding door for railway cars, more particularly to a door of this type for the side wall door opening of a box car; and the principal object of the invention is to provide a sheet metal door of novel and improved construction for use particularly in this situation which can be inexpensively manufactured and will be light in weight and at the same time strong and very rigid to withstand the hard usage to which box car side doors, because of their size, the way in which they are moved back and forth and their position on the outside of the car structure are peculiarly liable.

A further object is to provide certain novel arrangements for weatherproofing the edges of the door when closed.

The invention consists of the novel constructions, arrangements and devices to be hereinafter described and claimed for carrying out the above stated object and such other incidental objects as will be referred to in the following description of the preferred embodiment of the invention illustrated in the accompanying drawing. In the drawing,

Fig. 1 is a fragmentary side elevation of the door and door frame.

Fig. 2 is a vertical sectional view on line 2—2 of Fig. 1, and

Fig. 3 is a fragmentary sectional plan on line 3—3 of Fig. 1.

Referring to the drawing, 10 designates the side sheathing of the car, 11 the side sill, 12 the side plate, 13 the forward door post, 14 the rear door post and 15 the flooring of the car, the door opening being indicated by the space designated 16 (Fig. 3). The door is arranged to slide back and forth across the door opening 16, the term "forward door post" meaning the post at the edge of the door opening overlapped by the front edge of the door when closed, the term "rear door post" meaning the post at the other side of the door opening over which the door slides in opening and closing. The door posts and flooring preferably

project outwardly beyond the sheathing 10 as shown.

The door comprises a marginal, rectangular frame composed of members angular in cross section and a sheet metal panel secured to said frame and formed of one or more sheets of metal formed, preferably, with rigidifying corrugations. The marginal frame consists of an angle bar top member 17, the horizontal flange 18 of which projects inwardly from the front plane of the door, a Z-bar bottom member 19 arranged with its intermediate web 20 in horizontal position, an angle bar 21 arranged with one flange 22 in the front plane of the door and projecting rearwardly, and the other flange 23 projecting inwardly, and an angle bar 24 at the rear edge of the door with one flange 25 in the front plane of the door and the other flange 26 projecting inwardly and formed with an oblique lip 27 inclined forwardly. The sheet metal panel is composed, as shown, of three sheets of metal 28, 29 and 30 fastened together by rivets 31, the edges of said panel being secured flatwise to the depending flange 32 of the top member 17, the outer upstanding flange 33 of Z-bar 19, and to flanges 22 and 25 of the forward and rear angle bars 21, 24. The sheets 28, 29 and 30 are formed with rigidifying corrugations 34 which preferably taper and terminate at their extremities within the edges of the sheets, these corrugations being preferably horizontally disposed and being pressed inwardly from the marginal portions of the panel so that they occupy the space within the marginal frame of the door. The depth of the corrugations is approximately the width of the marginal frame and a flat plate 35 is preferably secured to the depending flange 36 of Z-bar 19 and to the lower one of the corrugations 34. The lower portion of the door, therefore, has a box-like construction which gives great strength and rigidity. This is an important feature because the lower part of the door is particularly liable to injury through shifting of the cargo. Moreover, the element 35 provides a smooth wear plate for bearing against the flooring 15 when the door is moved back and forth.

The door is provided with hangers 37 which preferably span the first of the corrugations 34, as shown, these hangers being

furnished with rollers 38, the latter being adapted to run on a channel-shaped track 39 secured to a lintel strip 40 secured to the front face of the side plate 12. The 5 track 39 is formed with a depending flange 41 which stands in front of the upper edge of the door. The marginal frame of the door projects inwardly into a recess 42 formed in the lintel 40.

10 The lower edge of the door is guided by brackets 43 secured to the side sill 11 and formed with upstanding lips 44 which overlap the depending flange 36 of Z-bar 19 this flange being preferably formed with 15 offsets 44' so placed as to engage with the lips when the door is closed to force the inner edge of the door toward the flooring 15.

An angle bar stop strip 45 is secured to 20 the forward door post 13. When the door is closed the angle bar at the front edge of the door bears flatwise against the outstanding flange 46 of the stop strip 45. This provides a reliable and strong stop for the 25 front edge of the door. The construction moreover, effectually prevents rain, dust, cinders and the like from entering the car at this point.

The rear door post 14 is recessed at 47 for 30 the side sheathing 10 and a weather strip 48 is arranged on the rear face of the outwardly projecting portion of the post. This strip consists of an angle bar having a flange 49 substantially flush with the front 35 face of the post with its edge bent inwardly and forwardly to provide a lip 50 adapted, when the door is closed, to be engaged by the lip 27 on the angle bar 24 at the rear edge of the door.

40 Realizing that the door construction above described might be changed in respect to certain details of construction without departure from my invention, I wish to be understood as claiming all modifications within the scope of the appended 45 claims.

This application is a division of my co-pending application Serial No. 379,807 filed May 8, 1920.

50 I claim:

1. A metal side door for a railway car adapted to slide on the outside of the car across the door opening comprising a sheet metal panel formed with rigidifying corrugations, a stiffening member angular in cross section secured to the lower edge of the panel, and a flat plate secured to the projecting portion of the stiffening member and extending upwardly to one of the corrugations of the panel above the same so as to constitute a hollow reinforcement for the lower edge of the door.

60 2. A metal side door for a railway car adapted to slide on the outside of the car across the door opening comprising a sheet

metal panel formed with horizontally disposed rigidifying corrugations, a stiffening member angular in cross section secured to the lower edge of the panel, and a flat plate secured to the stiffening member and to the 70 corrugated portion of the panel above the same providing a box-like structure at the lower portion of the door.

3. A metal side door for a railway car adapted to slide on the outside of the car 75 across the door opening comprising a sheet metal panel formed with inwardly projecting corrugations, a stiffening member at the lower edge of the panel and projecting inwardly therefrom, and a flat plate on the 80 inside of the panel secured to the corrugated portion of the panel and to said stiffening member.

4. A metal side door for a railway car 85 adapted to slide on the outside of the car across the door opening comprising a sheet metal panel formed with inwardly projecting horizontal corrugations, a Z-bar at the lower edge of the panel and projecting inwardly therefrom, and a flat plate on the 90 inside of the panel secured to one of said corrugations and to said Z-bar.

5. A metal side door for a railway car 95 adapted to slide on the outside of the car across the door opening comprising a sheet 100 metal panel formed with a plurality of horizontally disposed, inwardly projecting corrugations which terminate within the edges of the panel to provide flat margins at the forward and rear edges of the door, angle bars secured to said forward and rear margins and having webs inwardly projecting therefrom, an angle bar secured to the upper edge of the panel having an inwardly projecting web, a Z-bar secured to 105 the lower edge of the panel and projecting inwardly therefrom, and a flat plate on the inside of the panel at its lower edge secured to one of said corrugations and to said 110 Z-bar.

6. In combination with the body of a railway box car having a door opening, guide brackets below the opening and a track above the same, a metal door comprising a sheet metal panel formed with a plurality 115 of horizontally disposed, inwardly projecting corrugations which terminate within the edges of the panel to provide flat margins at the forward and rear edges of the door, angle bars secured to said forward and rear margins and having webs inwardly projecting therefrom, an angle bar secured to 120 the upper edge of the panel having an inwardly projecting web, a Z-bar secured to the lower edge of the panel and projecting inwardly therefrom, a flat plate on the inside of the panel at its lower edge secured to one of said corrugations and to said 125 Z-bar, the inner web of the Z-bar and the lower edge of said flat plate extending back 130

- of said guide brackets and hangers secured to the face of the door having rollers to engage said track.
7. A railway car door comprising a marginal frame consisting of members at the top, bottom and forward and rear edges which are angular in cross section with flanges lying in the front plane of the door and flanges projecting inwardly therefrom, and a sheet metal panel having its marginal edges secured flatwise to said first named flanges and formed with corrugations pressed inwardly from said marginal edges.
8. A railway car door comprising a marginal frame consisting of members at the top, bottom and forward and rear edges which are angular in cross section with flanges lying in the front plane of the door and flanges projecting inwardly therefrom, and a sheet metal panel having its marginal edges secured flatwise to said first named flanges and formed with corrugations pressed inwardly from said marginal edges to a depth corresponding substantially to the width of said marginal frame.
9. A railway car door comprising a marginal frame consisting of angle bars at the top, forward and rear edges having flanges in the front plane of the door and flanges projecting inwardly therefrom, and a Z-bar at the bottom, the intermediate web of which is horizontal and extends backwardly from the front plane of the door and a sheet metal panel having its marginal edges secured flatwise against the first named flanges of the angle bars, and the upwardly projecting flange of said Z-bar and formed with corrugations pressed inwardly from said marginal edges.
10. A railway car door comprising a marginal frame consisting of angle bars at the top, forward and rear edges having flanges in the front plane of the door and flanges projecting inwardly therefrom, and a Z-bar at the bottom, the intermediate web of which is horizontal and extends backwardly from the front plane of the door, a sheet metal panel having its marginal edges secured flatwise against the first named flanges of the angle bars and the upwardly projecting flange of said Z-bar and formed with corrugations pressed inwardly from said marginal edges, and a plate on the inside of said door secured to the depending flange of the Z-bar and to the sheet metal panel.
11. A railway car door comprising a marginal frame consisting of angle bars at the top, forward and rear edges having flanges in the front plane of the door and flanges projecting inwardly therefrom, and a Z-bar at the bottom, the intermediate web of which is horizontal and extends backwardly from the front plane of the door, a sheet metal panel having its marginal edge secured flatwise against the first named flanges of the angle bars and the upwardly projecting flange of said Z-bar and formed with corrugations pressed inwardly from said marginal edges, the inwardly projecting flange of said Z-bar and formed with horizontal corrugations pressed inwardly from said marginal edges, and a plate on the inside of said door secured to the depending flange of the Z-bar and to one of said corrugations.
12. In combination with the door frame of a railway box car, a weatherproofing strip on the rear door post having an inwardly and forwardly projecting lip and a door comprising a marginal frame consisting of members at the top, bottom and forward and rear edges which are angular in cross section with flanges lying in the front plane of the door and flanges projecting inwardly therefrom and a sheet metal panel having its marginal edges secured flatwise to said first named flanges, and corrugations pressed inwardly from said marginal edges, the inwardly projecting flange of the frame member at the rear edge of the door being formed with an oblique, forwardly projecting lip to engage the lip on said weatherproofing strip on the rear door post when the door is closed.
13. In combination with the door frame of a railway car and an angle bar stop strip on the forward door post provided with an outstanding flange and a door comprising a marginal frame consisting of members at the top, bottom and forward and rear edges which are angular in cross section with flanges lying in the front plane of the door and flanges projecting inwardly therefrom, and a sheet metal panel having its marginal flanges secured flatwise to said first named flanges and formed with corrugations pressed inwardly from said marginal edges, said door being supported so that the inwardly extending flange of the frame member at the forward edge of the door bears flatwise against the outwardly projecting flange on the stop strip when the door is closed.
14. In combination with the door frame of a railway car, a track arranged above the door opening, guide brackets below said door opening, and a door comprising a marginal frame consisting of members at the top and forward and rear edges which are angular in cross section with flanges lying in the front plane of the door and flanges projecting inwardly therefrom, and a Z-bar bottom member, the intermediate web of which is horizontally arranged and extends backwardly from the front plane of the door, a sheet metal panel secured to the first named flanges of said top, forward and rear members and to the upstanding flange of said Z-bar and formed with inwardly extending, horizontal corrugations, and a plate on the inside of the door secured to the depending flange of said Z-bar, and

to one of said corrugations, the lower edge of said plate and the depending flange of the Z-bar standing back of said guide flanges.

5 15. A railway car door comprising, in combination a marginal rectangular frame, a sheet metal panel, and a plate cooperating with said frame and panel to provide a hollow box-like structure at the lower edge 10 of the door.

16. A railway car door comprising, in combination, a sheet metal panel formed with horizontally disposed corrugations, and a Z-bar at the lower edge of the panel having an 15 upstanding flange to which the panel is secured, and an oppositely disposed depending flange, the intervening web of said Z-bar being substantially horizontal.

17. A railway car door the upper portion of which consists of a single thickness of 20 sheet metal provided with angular members for rigidifying its edges and formed with stiffening corrugations projecting into the space defined by said angular members and the lower portion of which consists 25 of a hollow box-like construction lying approximately between the planes on opposite sides of said corrugations.

18. A railway car door comprising, in combination a marginal rectangular frame 30 consisting of members angular in cross section, and a sheet metal panel formed with corrugations terminating within the edges of the sheet and projecting into the space within said frame.

WALTER P. MURPHY.
